(57) **ABSTRACT**

An exercise device comprising a first strap, a second strap, a buckle, and at least one section of padding coupled to an interior surface of the buckle. The first strap has a first end and a second end, and the buckle is fixedly coupled to the first end of the first strap and configured to receive and retain the second of the first strap. The buckle has a base coupled to the first end of the first strap and a handle portion movably coupled to the base by a pin. The second strap has a first end and a second end, wherein the second strap is fixedly coupled to the first strap, the first and second ends of the second strap having hook and loop fasteners coupled thereto and are configured to removably couple to each other. The second strap is configured to grip and retain at least one weight.

FIG. 1

Fig. 2.

FIG. 6

1

EXERCISE DEVICE FOR COUPLING
WEIGHTS TO A USER'S LEGCROSS-REFERENCE TO RELATED
APPLICATIONS

This application claims priority to U.S. Provisional Patent Application No. 63/475,667, titled "6-Pack-Strap," filed Dec. 5, 2022, and U.S. Provisional Patent Application No. 63/465,532, titled "6-Pack-Strap," filed May 11, 2023, the contents of which are incorporated by reference herein in their entirety.

BACKGROUND

Physical exercise is an important part of a healthy lifestyle. In recent years, it has become popular to exercise at home, or outside the gym. However, exercising outside the gym has the disadvantage of limited access to traditional gym equipment.

Accordingly, there is a need for an exercise device that aids users in exercising without the need for more traditional gym equipment.

SUMMARY

The present invention addresses this need. The present invention is directed to an exercise device comprising a first strap having a first end and a second end, a buckle fixedly coupled to the first end of the first strap and configured to receive and retain the second end of the first strap, and a second strap having a first end and a second end, wherein the second strap is fixedly coupled to the first strap. The first and second ends of the second strap are configured to removably couple to each other, and the second end of the first strap is configured to slide into and be retained by the buckle. Optionally the device also comprises at least one spacer.

Optionally, the first strap and the second strap each have a longitudinal axis, and the longitudinal axis of the first strap is perpendicular to the longitudinal axis of the second strap.

Optionally, the buckle comprises a base coupled to the first end of the first strap, and a handle portion movably coupled to the base by a pin.

Optionally, the first and second ends of the second strap have hook and loop fasteners coupled thereto, and the first and second ends of the second strap are configured to removably couple to each using the hook and loop fasteners.

Optionally, the device further comprises at least one section of padding coupled to an interior surface of the buckle.

A method of using the exercise device comprises the steps of a) providing the exercise device, b) securing at least one weight to the device using the second strap, c) optionally positioning the at least one spacer between the user's legs, d) securing the first strap to at least a portion of one of the user's legs, and d) lifting at least one of the user's legs.

Optionally, step c) is performed before step b).

DRAWINGS

These and other features, aspects, and advantages of the present invention will become better understood with regard to the following description, appended claims, and accompanying drawings.

FIG. 1 is a front perspective view of an exercise device having features of the present invention;

2

FIG. 2 is a front, exploded perspective view of the exercise device of FIG. 1;

FIG. 3 is a front perspective view of a method of using the exercise device of FIG. 1, wherein a handle portion of a buckle has been lifted, and an end of a first strap has been inserted into the buckle, and, at least one weight is positioned for coupling to the device by a second strap;

FIG. 4 is another front perspective view of the method of using the device of the FIG. 3, wherein the handle portion of the buckle is pressed downward, securing the end of the first strap therein, and the second strap has secured the at least one weight to the device;

FIG. 5 is a perspective view of a first step of one method of a user using the device of FIG. 1, wherein the device is secured to an upper portion of the user's leg;

FIG. 6 is a perspective view of a first step of a second method of a user using the device of FIG. 1, wherein the device is secured to a lower portion of the user's leg;

FIG. 7 is a perspective of the second step of either the first or second method of FIGS. 5 and 6, wherein the user lifts their leg to exercise;

FIG. 8 is top perspective view of a user using the device; and

FIG. 9 is a perspective view of the spacer.

25

DESCRIPTION

As used herein, the following terms and variations thereof have the meanings given below, unless a different meaning is clearly intended by the context in which such term is used.

The terms "a," "an," and "the" and similar referents used herein are to be construed to cover both the singular and the plural unless their usage in context indicates otherwise.

As used in this disclosure, the term "comprise" and variations of the term, such as "comprising" and "comprises," are not intended to exclude other additives, components, integers ingredients or steps.

All dimensions specified in this disclosure are by way of example only and are not intended to be limiting. Further, the proportions shown in these Figures are not necessarily to scale. As will be understood by those with skill in the art with reference to this disclosure, the actual dimensions and proportions of any system, any device or part of a device disclosed in this disclosure will be determined by its intended use.

Referring now to FIGS. 1 and 2, there is shown an exercise device 100 having features of the present invention.

The exercise device 100 has a first strap 102, a buckle 104, and a second strap 106. The first strap 102 has two opposed ends, a first end 108A and a second end 108B, and a longitudinal axis that extends along the length of the strap 102, from the first end 108A to the second end 108B. Optionally, the device 100 can be used with at least one spacer 150.

The buckle 104 has a base 110, a movable handle portion 112, and a pin 114 that movably secures the handle portion 112 to the base 110. The buckle 104 is configured to receive and securely retain the second end 108B of the first strap 102. The base 110 is fixedly coupled to the first end 108A of the first strap 102, which is looped through a portion of the base 110 and fixedly coupled to itself via stitching or some other permanent and secure method. The first end 108A of the first strap 102 that is looped through the base 110 is also fixedly coupled to a portion of strap 126. Coupled to the

portion of strap 126 is at least one section of padding 124, that is discussed in great detail below. This configuration can be best seen in FIG. 2.

The second strap **106** has two opposed ends, a first end **116A** and a second end **116B**, and a longitudinal axis that extends along the length of the strap **106**, from the first end **116A** to the second end **116B**. An interior surface **118** of the second strap **106** is fixedly coupled to an interior surface **120** of the first strap **102** and preferably, although not necessarily, the longitudinal axis of the first strap **102** is perpendicular to the longitudinal axis of the second strap **106**, and vice versa. The first and second ends **116A**, **116B** of the second strap **106** can have hook and loop fasteners **122** coupled thereto. Optionally, an external surface of the first strap **116A** has a half of the hook and loop fasteners **122A** coupled thereto, and an interior surface of the second end **116B** has the other half of the hook and loop fasteners **122B** coupled thereto.

Optionally, the ends of the second strap **116A**, **116B** can utilize some other type of removable fastening system to removably couple the ends of the second strap **116A**, **116B** to themselves. The other types of fastening systems can comprise snaps or a buckle or ratchet system.

The second strap **106** is configured to grip and retain at least one weight **300**. The weight **300** can be a dumbbell, as shown in the figures, or some other type/form of weight that can be used to achieve the same exercise result. The first and second ends **116A**, **116B** of the second strap **106** are configured to removably couple to each other using hook and loop fasteners **122A**, **122B**.

Optionally, there is more than one first strap **102** and/or more than one second strap **106** (not show). More than one first strap **102** increase the gripping ability of the device **100** to grip to a user and allow the device **100** to hold more weight. More than one second strap **106** allows the user to couple more than one weight to the first strap **102**, increasing the lifting capacity of the device **100**.

Optionally, but preferably, there is at least one section of padding **124** coupled to an interior surface of the section of strap **126**. The padding **124** provides comfort to the user **500** when the device **100** is strapped securely to a portion of at least one of their legs.

Referring now to FIGS. 3 and 4, the function of the buckle **104** and the gripping of the weight **300** by the second strap **106** are shown. FIG. 3 shows the handle portion **112** of the buckle **104** in an open, receiving position, where the handle **112** is pivoted upwards, away from the base **110**, allowing the second end **108B** of the first strap **102** to be slid through the open space between the handle **112** and the base **110**. Additionally, the second strap **106** is an open, receiving position wherein its two ends **116A**, **116B** are not coupled to each other, and the weight **300** can be inserted therebetween.

FIG. 4 shows the handle **112** in a closed, locked position, wherein the handle **112** is pivoted downwards, towards the base **110**, securing the second end **108B** of the first strap **102** therein. Pressure and gripping force are applied by the gripping portion **128** of the handle **112** to the second end **108B** of the strap, pinning the strap **108B** between the gripping portion **128** of the handle **112** and the base **110** of the buckle **104**. Additionally, the second strap **106** is now in a closed, retaining position, wherein its two ends **116A**, **116B** are coupled to each other and the weight **300** is securely retained therein.

The buckle **104** is not limited to the specific shape and configuration shown in the figures. The buckle **104** can have a different configuration, and any type of locking buckle that could be used in this device **100** that would allow the user to secure the first strap **102** tightly around at least a portion of one of their legs. Optionally, the buckle **104** can be a ratchet system.

Referring now to FIGS. 5 through 7, there is shown use of the device **100** in greater detail. A user **500** lays on the ground, or other flat surface, straps the weight **300** to the device **100** as shown in FIGS. 3 and 4, and then secures the device **100** to a leg portion using the first strap **102** and the buckle **104**. As shown in FIG. 5, the device **100** can be secured to at least one thigh portion of the user **500**. Alternatively, as shown in FIG. 6, the device **100** can be secured to at least one ankle portion of the user **500**. As shown in FIG. 6, the device **100** is secured to both ankles of the user **500**. It should be noted that the device **100** can be secured anywhere along at least one leg, or both legs, of the user **500**. Optionally, a device **100** can be secured to each leg of the user **500**. Optionally, more than one device **100** can be secured to a leg portion of the user **500**.

Optionally, at least one spacer **150** can be placed between the user's legs, anywhere along the length of user's legs, as shown in FIGS. 6 and 8. The spacer **150** functions as a cushioned spacer between the user's legs to increase the comfort level when using the device **100** as the user's knees are not pressing directly against each other. Additionally, the spacer **150** allows the user to comfortably apply inward pressure between their legs, such as by squeezing their legs together, which can increase the effectiveness of the exercise device **100** and allow the user to better engage their various core muscles. The spacer **150** can be made from any material that permits at least some slight compression so that it is comfortable for user to grip and squeeze between their legs. Preferably the spacer **150** is made from a foam material. The spacer **150** can be any shape and is not limited to the rectangular/cuboid shape shown in the figures. Optionally, the spacer **150** can have opposed side surfaces that are concave to form a slight recess for retaining each of the user's legs, or the spacer **150** can be spherical in shape.

Once one or more devices **100** are secured to the user's legs **500**, and/or the optional at least one spacer **150** is properly positioned between the user's legs, the user **500** then lifts their leg (or legs), pivoting at their hips, to performed a weighted leg exercise that works their core and abdominal region. This pivoting/leg lifting/leg lowering movement is shown in FIG. 7, and the leg(s) are lifted and lowered as many times as desired by the user **500**.

Optionally, the device **100** is secured to the user's **500** leg first, and then the weight **300** is secured to the device **100** using the second strap **106**. Once the weight **300** is coupled to the device **100**, the user **500** then performs the lifting/lowering leg movement shown in FIG. 7.

The straps **102**, **106** of the device **100** can be made from any sturdy strap material such as nylon, vinyl, cotton, or composite material. Preferably, the straps **102**, **106** are made from nylon. The straps **102**, **106** can be any width and length that can reasonably be utilized in this fashion. Preferably, the straps **102**, **106** are 2 inches wide and 40 inches long.

Although the present invention has been described in considerable detail with reference to certain preferred embodiments, other embodiments are possible. The steps disclosed for the present methods, for example, are not intended to be limiting nor are they intended to indicate that each step is necessarily essential to the method, but instead are exemplary steps only. Therefore, the scope of the appended claims should not be limited to the description of preferred embodiments contained in this disclosure. All references cited herein are incorporated by reference.

What is claimed is:

1. An exercise device comprising:
a) a first strap having a first end, a second end, and a longitudinal axis;

- b) a buckle fixedly coupled to the first end of the first strap and configured to receive and retain the second end of the first strap, the buckle having:
    - i) a base coupled to the first end of the first strap; and
    - ii) a handle portion movably coupled to the base by a pin;
  - c) a second strap having a first end, a second end, and a longitudinal axis, wherein the second strap is fixedly coupled to the first strap and the longitudinal axis of the second strap is perpendicular to the longitudinal axis of the first strap, the first and second ends of the second strap having hook and loop fasteners coupled thereto;
  - d) at least one section of padding coupled to an interior surface of the buckle; and
  - e) at least one spacer;
- wherein the second end of the first strap is configured to slide into and be retained by the buckle;
wherein the second strap is configured to grip and retain at least one weight, and the first and second ends of the second strap are configured to removably couple to each other using the hook and loop fasteners.

2. A method of using the device of claim 1, the method comprising:

- a) providing the device of claim 1;
- b) securing the at least one weight to the device using the second strap;
- c) positioning the at least one spacer between a user's legs;
- d) securing the first strap to a portion of at least one of the user's legs; and
- e) lifting at least one of the user's legs.

3. The method of claim 2, wherein step c) is performed before step b).

4. An exercise device comprising:

- a) a first strap having a first end and a second end;
  - b) a buckle fixedly coupled to the first end of the first strap and configured to receive and retain the second end of the first strap;
  - c) a second strap having a first end and a second end, wherein the second strap is fixedly coupled to the first strap, the first and second ends of the second strap configured to removably couple to each other; and
  - d) at least one section of padding coupled to an interior surface of the buckle;
- wherein the second end of the first strap is configured to slide into and be retained by the buckle.

5. The device of claim 4, wherein the first strap has a longitudinal axis and the second strap has a longitudinal

axis, and the longitudinal axis of the second strap is perpendicular to the longitudinal axis of the first strap.

6. The device of claim 4, wherein the buckle comprises:

- a) a base coupled to the first end of the first strap; and
- b) a handle portion movably coupled to the base by a pin.

7. The device of claim 4, wherein the first and second ends of the second strap have hook and loop fasteners coupled thereto, and the first and second ends of the second strap are configured to removably couple to each other using the hook and loop fasteners.

8. The device of claim 4, further comprising at least one spacer.

9. A method of using the device of claim 8, the method comprising:

- a) providing the device of claim 8;
- b) securing the at least one weight to the device using the second strap;
- c) securing the first strap to a leg portion of a user; and
- d) lifting the leg portion of the user.

10. The method of claim 9, wherein step c) is performed before step b).

11. A method of using the device of claim 4, the method comprising:

- a) providing the device of claim 4;
- b) securing the at least one weight to the device using the second strap;
- c) securing the first strap to a leg portion of a user; and
- d) lifting the leg portion of the user.

12. The method of claim 11, wherein step c) is performed before step b).

13. An exercise device comprising:

- a) a first strap having a first end and a second end;
  - b) a buckle fixedly coupled to the first end of the first strap and configured to receive and retain the second end of the first strap;
  - c) a second strap having a first end and a second end, wherein the second strap is fixedly coupled to the first strap, the first and second ends of the second strap configured to removably couple to each other;
  - d) at least one section of padding coupled to an interior surface of the buckle;
- wherein the second end of the first strap is configured to slide into and be retained by the buckle; and
and the first and second ends of the second strap are configured to removably couple to each other using a hook and loop fasteners.

14. The device of claim 13, further comprising at least one spacer.
